Primary Examiner — Darlington Ly

(57) **CLAIM**

The ornamental design for a two-wheel-drive off-road motorcycle, as shown and described.

DESCRIPTION

FIG. 1 is a top, front and right side perspective view of a two-wheel-drive off-road motorcycle showing our new design;

FIG. 2 is a top, rear and left side perspective view thereof; FIG. 3 is a bottom, rear and left side perspective view thereof;

FIG. 4 is a bottom, rear and right side perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof;

FIG. 10 is a bottom plan view thereof;

FIG. 11 is an enlarged view of portion 11 in FIG. 1; and,

FIG. 12 is an enlarged view of portion 12 in FIG. 3.

The broken lines in the drawings illustrate portions of the two-wheel-drive off-road motorcycle which form no part of the claimed design.

1 Claim, 12 Drawing Sheets
